(57) **CLAIM**

The ornamental design for a nasal aspirator, as shown and described.

DESCRIPTION

FIG. 1 is a perspective view of a first embodiment of a nasal aspirator showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarge view of portion 9 shown in FIG. 1;
FIG. 10 is an enlarge view of portion 10 shown in FIG. 1;
FIG. 11 is a perspective view of a second embodiment of the nasal aspirator showing my new design;
FIG. 12 is another perspective view thereof;
FIG. 13 is a front elevational view thereof;
FIG. 14 is a rear elevational view thereof;
FIG. 15 is a left side elevational view thereof;
FIG. 16 is a right side elevational view thereof;
FIG. 17 is a top plan view thereof;
FIG. 18 is a bottom plan view thereof; and,
FIG. 19 is an enlarge view of portion 19 shown in FIG. 11.
The broken lines in the drawings depict portions of the nasal aspirator that form no part of the claimed design.
